UNITED STATES PATENT OFFICE.

LOUIS MAUTNER, OF BROOKLYN, NEW YORK.

DESIGN FOR A BOWL OR SIMILAR ARTICLE OF SILVERWARE.

Application filed May 21, 1928. Serial No. 26,782. Term of patent 7 years.

To all whom it may concern:

Be it known that I, LOUIS MAUTNER, a citizen of the United States, residing at Brooklyn, in the county of Kings and State of New York, have invented a new, original, and ornamental Design for Bowl or Similar Article of Silverware, of which the following is a specification, reference being had to the accompanying drawing, forming a part thereof.

Figure 1 is a front elevation of the article showing my new design.

Figure 2 is a side elevation thereof.

The dominant feature of design is the particularly cut peripheral edge shown, in conjunction with the symmetrically designed body and parts, defining a sharp angular effect, known to the public as a "modernistic" pattern or design.

I claim:

The ornamental design for a bowl or similar article of silverware, as shown and described.

LOUIS MAUTNER.
